UNITED STATES PATENT OFFICE

2,652,021

MACHINE FOR COATING BACK SEAMS OF
SHOE UPPERS**Harry Phillips, Beverly, Mass., assignor to United
Shoe Machinery Corporation, Flemington, N. J.,
a corporation of New Jersey**

Application April 26, 1951, Serial No. 223,086.

5 Claims. (Cl. 118—2)

1

This invention relates to machines for applying flexible plastic material in liquid form to the back seams of shoe uppers. The machine is arranged to support the upper in an inside-out condition and to apply the plastic material to the seam ridge and the adjacent portions.

The back seam of a shoe upper is usually formed by placing the two quarters in superimposed position with the display faces in contact and stitching the parts together along a line close to their rear edges thus forming the back seam. It will be realized, however, that this seam must be spaced a sufficient distance from the edges so that there will be enough strength in the materials to prevent the stitches from pulling through the leather. As a result there is a projecting ridge on the inner face of the upper which may be a source of discomfort to the wearer and which is frequently reinforced as by means of a strip of fabric secured adhesively over the ridge. Before such a strip is applied it is customary practice to flatten the seam by pressure usually applied progressively. Some instances have been found where there has been an oozing of the counter paste through the back seam.

An important object of the present invention is to provide an improved machine for applying a flexible plastic coating to the back seams of shoes. One feature of the invention resides in the provision, in such a machine, of a U-shaped frame on opposite arms of which are mounted driven feed rolls. These feed rolls coat with an upper which is supported upon a rotatable supporting roll between the feed rolls and the application of the plastic material is effected by extrusion through a nozzle disposed above the seam ridge.

The mounting of the feed rolls is such that the upper is drawn down tightly over the supporting roll at the same time that the feed rolls are effective to carry the seam progressively past the extruding nozzle through which material is applied to cover the seam ridge and, it may be, to fill the hollows on either side of that ridge.

The desirability of preventing the extrusion of the coating material upon the supporting roll of the machine between successive pieces of work will be obvious and in accordance with another feature of the invention, a sensitive feeler is provided which rests upon the upper ahead of the nozzle as it passes through the machine and is effective to actuate a power means for shutting a valve located in the passage between a pressure-providing pump and the nozzle, thus

2

stopping the flow of coating material before the work leaves the nozzle.

These and other features of the machine will best be understood from a consideration of the following specification, taken in connection with the accompanying drawings, in which

Fig. 1 is a front elevation of the machine;

Fig. 2 is a side elevation thereof;

Fig. 3 is an enlarged detail, partly in section, taken on the line III—III of Fig. 2;

Fig. 4 is a detail of the control valve for the nozzle with a piece of work supported in the machine for treatment;

Fig. 5 is a detail, in front elevation, of a supporting roll and an upper at the point of contact of the feeler; and

Fig. 6 is a view of the end face of the nozzle showing one particular contour of its work contacting end.

20 The illustrative machine is arranged for operation upon a work piece W, a fragment of which is shown in Figs. 4 and 5, which comprises a pair of quarters joined together by a line of stitching S and turned inside out, leaving a seam ridge R. Before treatment here, the seam will usually have been pressed or reduced, as shown in Fig. 5. As presented to the coating machine, the ridge R projects upwardly and the work piece rests upon a work support comprising a stationary center disk 10, with rounded recesses

30 11, and upon a supporting roll having freely rotatable frusto conical side portions 12. The work is guided over this support by means of a guide 14 received in the seam crease, said guide having a bulge 15 at its end which is received in one of the recesses 11 to hold the disk 10 against rotation. A feeler 16, grooved to straddle the seam, rests on the upper at each side of the seam ridge R. As the work passes beneath a nozzle 18, which may be provided with a notch

40 20 (Fig. 6) coating with the seam ridge R, it is fed along by feed rolls 22 which will be later described and which pull the work progressively past the nozzle and draw it tightly over the work support 10, 12.

45 These operating instrumentalities are mounted upon a frame having a base 24 (Fig. 1), a cross rib 25, and an upright 26. The latter is provided with a laterally extending web 28 carrying an extruding means E (Fig. 1) and with a bracket 30 supporting the driven feed rolls 22. The outer portion of the bracket is substantially U-shaped as may be seen from Fig. 3 and has a drive shaft 32 passing through the top of the inverted U. The side portions of the U-shaped bracket are

hollowed to receive trains of driving gears 34 protected by end covers 35 and 37. The gears 34 impart rotation to the stub shafts 36 and 38 on which are carried the feed rolls 22. These rolls as may be seen from Fig. 3 are frusto conical in axial section and have toothed faces for engaging the inner surfaces of the work piece on either side of the back seam. The shaft 38 is fixed against end play in the bracket while the shaft 36 is provided with an internally contained spring 40 by means of which it is urged axially to insure that the work is gripped frictionally by the feed rolls against the work support rolls 12. In principle, this arrangement is substantially like that shown in Letters Patent of the United States No. 2,513,464, granted July 4, 1950, on the application of H. D. Elliott. These rolls 22 are driven both in the same direction as indicated by the arrows in Fig. 5 and are disposed so that they are effective first to draw the upper tightly over the top of the supporting rolls 12 and then to carry it forward beneath the nozzle 18. Power for operating the drive shaft 32 is supplied through an extension shaft 42 journaled in a bearing (Fig. 1) in the upright 26 and connected by sprocket and chain 44 to a driven power shaft 46 provided with fast and loose pulleys 48 and 50.

The stationary work supporting roll 10, held against turning by the end of the seam crease guide 14, is mounted on a pivot 51 in a plunger 52 (Fig. 2) yieldably mounted in a carrier 54, substantially as described in the above-mentioned patent to Elliott. This carrier is secured to a tiltable plate 56 which is pivotally mounted by means of a rod 57 in a block 58 on the base and may be locked in the operative position illustrated in the drawings by a spring pin 60, having a handle 62, and cooperating with a socket 64 (Fig. 1) in said block 58. If the work pieces being treated are closed uppers, these are allowed to accumulate in a stack around the upstanding portion of the carrier 54 and may readily be removed by pulling out the spring-pressed bolt 60 and tilting the carrier forward out of operative relation to the driven parts of the machine. This carrier is also utilized for supporting the seam crease guide 14.

The nozzle 18, through which the flowable material is delivered to the seam ridge R and the adjacent portions of the work W, is constructed substantially as shown in Figs. 7 and 8 of Letters Patent of the United States No. 2,353,738, granted July 18, 1944, upon the application of W. L. MacKenzie except that the work contacting end has a different contour. The nozzle comprises an inner plate 70 (Fig. 4) and an outer plate 72 which are attached by means of screws to a valve block 74. The inner plate 70 is provided with an inlet opening 76 connecting with a groove 78 in that plate. The lower end of the groove 78 communicates with a recess 80 in the other plate (see also Fig. 6). It will be noted that the plate 70, which rests upon the work, is slightly longer than the plate 72 the lower end of which is spaced above the work and thus determines the thickness of the coating applied.

In the valve block 74 is a valve 81 having an annular seat closed by a conical head 82 on a stem 84 which is slidably mounted in a packing block 86 and pressed against the annular seat by means of a spring 88. This valve is situated in a passage 90 joining the inlet 76 of the nozzle and to which the flowable material is supplied through a vertical passage 92 communicating with the

outlet of a gear pump 94 (Fig. 2) contained within a chamber at the bottom of a casing 96 to which this valve block 74 is secured. The casing 96 also includes a receptacle 100 having a sloping bottom 102 and provided with a heating unit 104. The latter is operated under the control of a thermostat 106. The gear pump 94 is driven by power supplied to a vertical shaft 110 connected by spiral gears to a horizontal shaft 112 (Fig. 1) having a pulley 114 driven by a crossed belt 115 leading to a pulley 116 on the shaft 42. A screw having a thumb piece 118 controls the tension of a spring pressing against a valve (not shown) in a by-pass around the pump, thus regulating the pressure at the nozzle.

Power to operate the movable valve head 82 is supplied by a solenoid 120 supplied from any suitable source and mounted on the web 28 of the frame. The solenoid has a core which is mechanically connected to a two-arm lever 122, 123 pivoted in a bracket 124 forming part of a plate 126 which is screwed to the casing 96 of the extruding apparatus E. The upper portion 122 of the solenoid-operated lever is pinned to a shaft 128 at the right end of the bracket 124 (Fig. 1) while the depending slotted lower end 123 of the lever is mounted on the other end of the shaft 128 in a forked end 130 of the bracket 124. This slotted end 123 engages a cross pin 132 (Figs. 2 and 4) in a block 134 on a stem 84 of the valve and abutting a nut thereon. When the solenoid is energized the lever 122, 123 is effective to open the valve 81 against the tension of its spring 88.

The feeler 16, with its grooved lower end straddling the seam ridge R (Fig. 5), is supported on a rod 140 journaled in a bracket 142 (Fig. 1), attached by a screw to the bracket 30 which supports the feed rolls, and is provided with an upwardly extending arm 144 secured to the end of the rod 140 and having a stop screw 146 which engages a portion of the bracket 30 to limit the downward movement of the feeler 16. The upper end of the arm 144 is connected by an adjustable link 148 (Fig. 2) to a bell crank 150 pivoted in a block 152 also attached to the bracket 30. The outer end of the bell crank is positioned beneath a button 154 on a sensitive switch 156 in circuit with the solenoid winding. The switch is carried by the web 28 with the result that a very small movement of the feeler 16 is sufficient to energize the solenoid 120. Inasmuch as the feeler 16 is placed in front of the nozzle 18 (Fig. 2) it will actuate the switch 156 slightly before the work reaches the nozzle, thus giving time for the small amount of plastic between the valve head 82 and the nozzle outlet to be set in motion so that there is no delay in applying the plastic to the work. For the same reason the work will leave the feeler 16 before it leaves the nozzle and thus allow any surplus material in the nozzle itself to ooze out on the work rather than to be deposited on the other parts of the machine.

In the operation of the machine, the back seam crease of an everted upper is placed on the seam crease guide 14 and moved forward over the idle work supporting roll 10 until the seam ridge enters the groove in the lower end of the feeler 16 and the laterally adjacent parts of the upper raise the feeler and operate the switch 156 to energize the solenoid 120 thereby opening the control valve 81. Slightly after the work reaches the nozzle 18 it will be engaged by the rotating feed rolls 22 and stretched over the frusto conical sides 12 of the supporting roll. At the same time

it will be carried forward to move the back seam progressively beneath the nozzle 18 thus applying a coating of flowable plastic material which will form, as soon as it is allowed to dry, a tough flexible covering. As soon as the trailing edge of the upper passes under the feeler 16, the switch 156 will be released to deenergize the solenoid 120 and the valve head 82 will be closed by its spring 83. There will be time enough, however, between the time when the edge of the upper leaves the feeler and the time when it gets to the nozzle for any residual material under pressure in the nozzle passage to ooze out and be applied to the seam ridge rather than to drip on the work supporting roll 10, 12. It thus appears that the back seam is stretched as it is treated and that the resulting coating is applied to a well conditioned seamed upper which, when turned right side out, will have no undue fullness in the leather adjacent to the seam.

Having thus described my invention, what I claim as new and desire to secure by Letters Patent of the United States is:

1. In a machine of the character described, a frame, a work supporting roll carried thereby having frusto conical side faces, said frame having a U-shaped bracket, frusto conical feed rolls mounted in the sides of said bracket and cooperating with an upper on said supporting roll to draw it tightly over said roll and to carry it forward, a nozzle on the frame directly above said supporting roll, and means for extruding a flowable material through said nozzle for application to the seam ridge of an upper on the supporting roll.

2. In a machine of the character described, a support for an everted back seam of a shoe upper, said seam forming a ridge, means for engaging the upper at opposite sides of the seam ridge to press it against the support and move it progressively over said support, means adjacent to the support to apply a flowable material to the back-seam ridge, and means responsive to the presence of a piece of work on the support for delivering material to the applying means.

3. In a machine of the character described, a support for an inverted back seam of a shoe up-

per, means beside the support for engaging the upper at opposite sides of the seam ridge for moving it progressively over said support, a nozzle positioned over the support, means to supply flowable material under pressure to said nozzle, a control valve interposed between the nozzle and the supply means, and a movably mounted work-feeler-means for operating said valve.

4. In a machine of the character described, a support for an inverted back seam of a shoe upper, said seam forming a ridge, driven means for engaging the upper on the support at opposite sides of the seam ridge for moving it progressively over said support, a nozzle supported adjacent to the work support and positioned over the back seam, means to supply flowable material under pressure to said nozzle, a control valve interposed between the nozzle and the supply means, a solenoid to operate said valve, a switch for said solenoid, and a work-engaging feeler operatively connected to said switch to control said valve-operating solenoid.

5. In a machine of the character described, a frame, a support thereon for an inverted back seam of a shoe upper, rolls on the frame for engaging the upper at opposite sides of the seam ridge to draw it against the support and to move it progressively over said support, a nozzle on the frame and having its outlet adjacent to the back seam of an upper on the support, power-operated means to supply flowable material under pressure to the nozzle, a control valve interposed between the supply means and the nozzle, a power-actuated device for operating said valve, and a sensitive feeler resting on the work carried by the support ahead of the nozzle controlling the power device which operates the valve.

HARRY PHILLIPS.
